UNITED STATES PATENT OFFICE.

JACOB F. GIBSON, OF RED LION, PENNSYLVANIA.

CARRIAGE-LAMP AND FOOT-WARMER.

SPECIFICATION forming part of Letters Patent No. 321,713, dated July 7, 1885.

Application filed February 24, 1885. (No model.)

To all whom it may concern:

Be it known that I, JACOB F. GIBSON, of Red Lion, in the county of York and State of Pennsylvania, have invented certain new and useful Improvements in Combined Carriage-Lamps and Foot-Warmers; and I do declare that the following is a full, clear, and exact description of the invention, which will enable others skilled in the art to which it applies to make and use the same, reference being had to the accompanying drawings, and to the letters of reference marked thereon, which form part of this specification.

My invention relates to the utilization of a carriage-lamp in giving light to the driver from the lamp and heat to the feet by a chamber within and arranged on the bottom of the carriage, through which the heat from the burning oil of the lamp circulates.

This invention is an improvement on patent granted to me July 8, 1884, No. 301,713; and while the said patent covers valuable improvements, still I find some defects which I have in the present invention remedied.

To this end my invention consists, first, in the peculiar construction and arrangement of the bottom of the lamp, whereby the wind and air admitted to the lamp is controlled according to its irregularity—that is to say, when the wind is very high it may be shut off entirely from the bottom when the air to support combustion is supplied from the top. When the wind is moderate it may be partially shut off from the bottom, and when calm the valves may be wide open.

One of the great difficulties of using carriage-lamps for foot-warmers is to maintain a regularity of light, and therefore heat, and to properly utilize and distribute this heat without constantly being troubled by attending to the lamp.

The second feature of my invention is the combination, with the top plate of the structure, of a hood or cone-shaped deflector arranged over the top of the chimney. This is essential to the perfect burning of the lamp, for the reason that the top of the frame-work must be open to the atmosphere for the supply of the proper quantity of air; and when so open the air blowing in frequently extinguishes the lamp. To provide against this I place a hood or deflector over the lamp-chim-

ney, which when the wind blows in it is deflected downward, where it becomes harmless.

The third feature of the invention is the arrangement of valves and parts by which when the heat is not required it may be turned off from the heater without passing into it; and the fourth feature is in the construction of the heater and its arrangement in combination with the lamp.

Referring more particularly to the drawings, in which like letters denote like parts in the several figures, Figure 1 is a side elevation of a buggy having my invention attached, partly in section. Fig. 2 is a perspective view of the lamp and heating device complete and detached from the buggy. Fig. 3 is an inverted bottom plan view showing the perforated box and the valves, one being opened to show the method of operation. Fig. 4 is a vertical longitudinal section of the complete heating-apparatus, frame and lamp, and blind taken on the line *xx*, Fig. 2. Fig. 5 is a vertical longitudinal section of the lamp only, taken on the line *yy*, Fig. 4, showing a side view of the valve and port. Fig. 6 is a longitudinal and horizontal section through the valve-ducts and chamber on the line *zz*, Fig. 4, clearly illustrating the construction and arrangement of escape-flue and side valves and ducts; and Fig. 7 shows a cap for the lamp when the foot-warmer is removed and not necessary, the lamp still being required. Fig. 8 is a detail top plan view of the valve.

A is the carriage; B, the lamp, and C the foot-warmer. The bottom of the buggy or carriage separates one from the other.

D is a deflecting plate within the foot-warmer, arranged immediately over the lamp-chimney and extending nearly midway its length. The object of the plate D is to distribute the heat of the lamp. It has been found that when there is no deflector the heat at the chimney end is too great and not sufficient at the other, but with the deflector they are both just right.

The foot-warmer is provided with an inlet and an outlet conduit, E F, the inlet being much larger. By this means the products of combustion in passing are retarded and made to give up their heat more readily than if passed out in an uninterrupted current. The thimbles or short sections of pipe which form the

walls of the conduits extend through the bottom of the carriage and connect at one end with the lamp-chimney, and at the other with the atmosphere.

5 Between the lamp and the bottom of the carriage there are two plates, G H, interposed, from the latter of which the lamp-frame B is suspended. These plates are secured together by hollow stays or thimbles a a, which correspond with angle-irons b b, through which angle-irons and thimbles bolts c c pass. These bolts secure the lamp and plates to the bottom of the carriage when in position.

Between the plates G H, I locate the slide-valve d. (Shown in detail at Fig. 8.) The object of the valve is to shut off the products of combustion and direct them into outlet-conduits e f when the heat is not required in the foot-warmer. The valve d has an open aperture, g, on its flat side, and around its two sides and end a flange, h, which registers with side parts, i i, that open into the exit-flues e f for carrying off the smoke when the aperture g is closed.

25 Above the chimney of the lamp, and preferably secured to the plate H, is the hood and deflector I, which prevent the gushes of wind from the top entering the top of the lamp-chimney and extinguishing the light. This feature is very important and essential to the successful working of the lamp. I am aware it is common to put an ordinary shade over a lamp-chimney, but for an entirely different purpose from this. Mine is differently constructed, and with different combinations, and is suspended from the plate above.

40 It will be observed that the lamp is triangular in shape, on which I claim nothing; but at the bottom an air-conduit is arranged on each side of the oil-reservoir, the tops of which are perforated. The bottoms are open to the atmosphere except in storms, when they are closed by dampers or valves K. These valves K K are pivoted at one end and held in position by a cross-strap, l, as seen at Fig. 3.

45 The operation of this apparatus is obvious, except, perhaps, the valves for controlling the heat to the foot-warmer, which is as follows: For instance, the valve d is open, as shown at Fig. 4, the heat passing directly into the foot-warmer, and I desire to cut it off. I push the valve d into its innermost position. The valve having the side and end flanges immediately uncovers the ports i i leading into exit-flues

55 e f. The smoke passes into these exit-flues and off to the atmosphere beneath the carriage. It may sometimes happen that the plate carrying the valve and inlet-tubes gets so hot as to endanger the scorching of the bottom of the carriage. I provide against such 60 a contingency by forming an air-space between the two plates, through which external air is continually passing, and by which the plate in contact with the bottom of carriage is kept perfectly cool.

65 5 To provide against the glass of the lamp becoming muddy in daytime from splashing, when the light is not necessary, blinds or protecting-plates may be used which can be readily removed.

70 Any ordinary means may be employed to prevent the lamp-wick from turning down from the jolting of the vehicle. There extends up from the top plate a thimble, which is solidly fixed to said plate to prevent any water that 75 may find its way on the top from entering the lamp-chimney. The thimble E of the foot-warmer fits over the one extending from the top plate and over the lamp.

75 5 Having described my invention, what I claim is—

1. The combination of the lamp B, having chambers j j constructed with perforations, with the valve beneath, pivoted to operate to close said chambers, substantially as set forth.

80 5 2. The combination of the lamp B, having chambers j j constructed with perforations, with the upper and lower plates, G H, and the valve d, interposed between said plates, as set forth.

85 5 3. A combined carriage-lamp and foot-warmer, consisting of the lamp b and foot-warmer C, provided with valve d, interposed between them, said valve having a vertical aperture and side apertures arranged to operate 90 substantially as set forth.

90 5 4. The combination, with a foot-warmer proper, of the lamp B, having plates G H and passages therethrough, and controlling-valve d, with the deflector I, and thimbles between the plates, substantially as set forth.

100 In testimony that I claim the foregoing as my own I affix my signature in presence of two witnesses.

JACOB F. GIBSON.
